(57) **CLAIM**

The ornamental design for a task chair, as shown and described.

DESCRIPTION

This application is related to U.S. Design patent application Ser. Nos. 29/811,952 and 29/811,953, both filed Oct. 18, 2021.

FIG. 1 is a front, top, right side perspective view of a task chair, showing our new design;

FIG. 2 is a front elevation view of the task chair shown in FIG. 1;

FIG. 3 is a rear elevation view of the task chair shown in FIG. 1;

FIG. 4 is a left side elevation view of the task chair as shown in FIG. 1;

FIG. 5 is right side elevation view of the task chair as shown in FIG. 1;

FIG. 6 is a top plan view of the task chair shown in FIG. 1; and,

FIG. 7 is a bottom plan view of the task chair shown in FIG. 1.

The broken lines illustrate environmental structure which forms no part of the claimed design.

1 Claim, 7 Drawing Sheets
